UNITED STATES PATENT OFFICE.

ROBERT M. DOWNIE, OF BEAVER FALLS, PENNSYLVANIA, ASSIGNOR TO KEYSTONE DRILLER CO., OF BEAVER FALLS, PENNSYLVANIA, A CORPORATION OF PENNSYLVANIA.

ENGINE.

No. 878,783.

Specification of Letters Patent.

Patented Feb. 11, 1908.

Application filed August 13, 1907. Serial No. 388,333.

To all whom it may concern:

Be it known that I, ROBERT M. DOWNIE, a citizen of the United States, residing at Beaver Falls, in the county of Beaver and State of Pennsylvania, have invented a new and useful Engine, of which the following is a specification.

This invention relates more particularly to explosive engines of the reciprocatory piston type, and the object thereof broadly stated, is to provide novel means of a simple and effective nature for supplying either a lubricating or cooling agent or both to the piston.

In its more specific aspect, the invention aims to provide means of a practical nature, which will automatically take up the lubricant or a cooling agent from a reservoir and deliver it to the piston and associated parts that are subject to friction and heat, said means insuring a constant supply under pressure as long as the engine is in operation.

The preferred embodiment of the invention is illustrated in the accompanying drawings, wherein:

Figure 1 is a vertical sectional view through the engine. Figs. 2, 3, 4 and 5 are respectively horizontal sections on the lines 2-2, 3-3, 4-4 and 5-5 of Fig. 1. Fig. 6 is a detail sectional view through the lower portion of the piston taken at right angles to Fig. 1.

Similar reference numerals designate corresponding parts in all the figures of the drawings.

In the embodiment illustrated, a crank casing 7 is provided, including a column 8 that carries the cylinder member 9. A reciprocatory piston, operating in the cylinder member, comprises a shell 10 having an end wall 11 and cylindrical side walls 12. The side walls are provided with sets of radially disposed channels 13 leading to the outer face of the piston which is in sliding engagement with the inner face of the cylinder. Bearing sections are detachably fitted in this shell, the upper section being in the form of a cap 14 that is snugly fitted in the upper portion of the shell, and is provided with an upper series of radiating fingers 15 and a lower annular flange 16. The lower section 17 is threaded, as shown at 18 into the shell, and constitutes means for maintaining the cap section in place. A rotatable crank 19

operates in the crank casing 7, and a pitman 55 20 having its lower end connected to said crank, is provided at its upper end with a ball 21 having a bearing between the sections and partially in each, as will be clear by reference to Fig. 1.

The upper or cap section 14 is provided in its top with a chamber 22 closed by the end wall 11 of the shell, and an annular chamber 23, surrounding the ball bearing, is in communication with the uppermost chamber 22 65 through channels 24. This annular chamber 23 is in communication with the uppermost set of channels 13, and inwardly extending channels 25, lead from the chamber 23 to the bearing. The lower or retaining 70 bearing section 17 has its upper corner cut away to produce a chamber 26 in communication with the chamber 23 through channels 27, and this lower section is furthermore provided with another chamber 28 in communication with the chamber 26 through 75 channels 29, said chamber 28 being also in communication with the lowermost set of channels 13.

The pitman is provided with a longitudinal channel 30, and therefore constitutes a conduit. This channel 30 communicates with the lower end of an air chamber 31, formed in the upper end of said pitman, and a discharge conduit 32, depending into the 85 air chamber and having its lower inlet end located in the lower portion thereof, has its upper end opening through the top of the ball and communicating with a supply channel 33 leading to the uppermost chamber 22. 90 An upwardly opening ball valve 34 is preferably employed to permit the upward passage of fluid through the conduit 32, while preventing its return. In the lower portion of the channel 30 in the pitman is an upwardly 95 opening ball valve 35 and a curved supply conduit 36, has its upper end communicating with the channel 30 below the valve 35. The conduit 36 partially surrounds the crank 19, and is disposed eccentrically thereto, being provided with a lower open inlet end 37 that is disposed closer to the axis of the crank 19 than any other portion of the conduit. This is an important feature of the invention for the reasons hereinafter set forth. Access 105 to the interior of the crank casing is secured through a suitable door 38 located at one side of the same, and said casing, as clearly illus-

trated in Fig. 1, constitutes a reservoir for a fluid 39 which may be a lubricant, a cooling agent or both.

None of the valve mechanism, charge supplying means, or ignition mechanism is disclosed in the drawings, inasmuch as they constitute no part of the present invention, and may be of any suitable character.

The operation of the structure is substantially as follows. As the piston reciprocates, it will of course be understood that the crank 19 is revolved in the ordinary manner and in the direction of the arrow. Therefore the inlet end 37 of the conduit 36 will be forced through the fluid 39 and elevated therefrom, its movement closely resembling that of a pendulum, except that it is elevated and lowered, and as it passes through the liquid, a portion of said liquid will be forced through the inlet end and through the conduit into the channel 30 of the pitman, this introduction being due to the inertia of the fluid. Moreover, inasmuch as the conduit 36 is disposed eccentrically to the axis of the crank 19, and the inlet end 37 is located nearer said axis than any other part of the conduit, the fluid will be elevated with considerable force, inasmuch as its movement is continuously away from the crank, and consequently centrifugal force will assist in the operation. The fluid upon each successive movement of the conduit 36 through the reservoir will be elevated through the channel 30, and will reach the air chamber 31, finally passing through the conduit 32, past the valve 34 and being sprayed against the end wall 11 of the piston in the chamber 22. From this chamber it flows into the chamber 23, and thence part will pass through the channels 13 to the surface of the piston, while other portions are passed through the channels 25 to the pitman bearing. Other portions will gravitate to the lower chambers and thence to the piston surface, finally escaping and returning to the reservoir. Inasmuch as the escape from the piston will be comparatively slow, the supply will cause the fluid to accumulate in the lower portion of the air chamber 31 and passing above the lower end 50 of the discharge conduit 32, will compress the air in said chamber. Therefore a constant pressure is maintained by the compressed air so that the proper flow of the fluid through the different channels is insured.

From the foregoing, it is thought that the construction, operation, and many advantages of the herein described invention will be apparent to those skilled in the art, without further description, and it will be understood that various changes in the size, shape, proportion, and minor details of construction, may be resorted to without departing from the spirit or sacrificing any of the advantages of the invention.

Having thus fully described my invention,

what I claim as new, and desire to secure by Letters Patent, is:

1. In an engine of the character described, the combination with a cylinder member, of a piston member operating therein, a pitman having a bearing in the piston member, said piston member having a chamber, and a channel leading to the bearing, and means for supplying fluid to the chamber. 70

2. In an engine of the character described, the combination with a cylinder member, of a piston member operating therein, a pitman having a bearing in the piston member, said piston member having a chamber surrounding the bearing and a plurality of channels 80 leading to the bearing, and means for supplying fluid to the chamber. 75

3. In an engine of the character described, the combination with a cylinder member, of a piston member operating therein and having a chamber and channels leading therefrom to the surface of the piston member, and means for supplying fluid to the chamber. 85

4. In an engine of the character described, the combination with a cylinder member, of a piston member operating therein and having an annular chamber, and radial channels leading therefrom to the surface of the piston member, and means for supplying liquid to the chamber. 90

5. In an engine of the character described, the combination with a cylinder member, of a piston member operating therein, and a pitman having a bearing in the piston member, said piston member having a chamber 100 and channels leading therefrom to the bearing and to the surface of the piston member.

6. In an engine of the character described, the combination with a cylinder member, of a piston member operating therein, and a pitman having a bearing in the piston member, said piston member having an annular chamber surrounding the bearing and being furthermore provided with inwardly extending channels leading from the chamber to 110 the bearing and outwardly extending channels leading from the chamber to the surface of the piston member. 105

7. In an engine of the character described, the combination with a cylinder, of a piston 115 having a plurality of chambers and channels leading from the chambers to different portions of the surface of the piston, and means for introducing a fluid to said chambers.

8. In an engine of the character described, the combination with a cylinder member, of a piston member having upper and lower chambers, channels connecting the chambers, channels leading from the different chambers to different portions of the surface 125 of the piston, and means for supplying fluid to the upper chamber.

9. In an engine of the character described, the combination with a cylinder member, of a piston member operating therein and in- 130

cluding bearing sections, said sections having chambers therein, a pitman having a bearing in said sections, channels leading from the chambers to the bearing and to the surface of the piston, and means for supplying fluid to the chambers.

10. In an engine of the character described, the combination with a cylinder, of a reciprocatory piston operating therein and comprising a shell having channels through its peripheral wall, bearing sections fitted in the shell and having chambers in communication with the channels, a pitman having a bearing in the sections, said pitman having a channel therethrough that is in communication with the chambers, and means for supplying liquid to the pitman channel and through the same to the chambers.

11. In an engine of the character described, the combination with a cylinder and a reciprocatory piston operating therein, of a fluid holding reservoir, a crank in the reservoir, a pitman connected to the piston and to the crank, said pitman having a fluid conducting channel, and a curved inlet conduit located eccentrically to the axis of the crank and communicating with the fluid conducting channel of the pitman, said conduit having an open inlet end disposed nearer the said axis of the crank than any other portion of the conduit.

12. In an engine of the character described, the combination with a cylinder, of a reciprocatory piston operating therein and including an end wall, a pitman connected to the piston, and means for projecting fluid through the pitman and against the end wall.

13. In an engine of the character described, the combination with a cylinder, of a reciprocatory piston operating therein and including a shell having an end wall, a bearing section located in the shell and having a chamber in its top closed by said end wall, and means for projecting fluid into said chamber and against the end wall.

14. In an engine of the character described, the combination with a cylinder, of a reciprocatory piston operating therein and including a shell having an end wall, a bearing section located in the shell and having a chamber in its top closed by said end wall, a pitman having a bearing in said section, channels formed in the pitman and section and communicating with the chamber, and means for forcing fluid through the channels.

15. In an engine of the character described, the combination with a cylinder, of a piston operating therein, means for supplying fluid to the piston, including an air chamber having a fluid discharge channel that delivers to the piston, and means for introducing fluid into the chamber to compress the air therein, said compressed air constituting

means for ejecting said fluid through said discharge.

16. In an engine of the character described, the combination with a cylinder, of a reciprocatory piston operating therein, means for supplying fluid to the piston including an air chamber, a fluid discharge conduit having an inlet opening in the lower portion of the chamber, and means for introducing fluid under pressure into the lower portion of the air chamber to compress the air in the upper portion thereof.

17. In an engine of the character described, the combination with a cylinder, of a piston operating therein and having discharge passageways, a pitman connected to the piston and having an air chamber in the upper end thereof, and a channel leading to the lower portion of said air chamber, means connected to the channel for introducing fluid thereinto, and a discharge conduit communicating with the discharge passageways of the piston and having its inlet end in the lower portion of the air chamber.

18. In an engine of the character described, the combination with a crank case constituting a fluid reservoir, of a cylinder mounted on said crank case, a reciprocatory piston operating in the cylinder and comprising a shell having an end wall and radial channels in its side walls, a cap bearing-section located in the shell and having a chamber communicating with certain of the radial channels, said cap section having an annular chamber that communicates with the first mentioned chamber, another bearing section threaded into the shell and having a chamber communicating with certain of the radial channels and being also in communication with the chambers of the cap section, a rotary crank located in the crank case, a pitman connected to the crank and having a ball bearing in the bearing section, said pitman having an air chamber in its upper portion, and a fluid conducting channel communicating with the lower portion thereof, a discharge conduit depending into the air chamber and having its inlet end in the lower portion thereof, said conduit being in communication with the chamber in the top of the cap section, and a curved supply conduit partially surrounding the crank and having its upper end communicating with the chamber of the pitman, said supply conduit being disposed eccentrically to the axis of the crank and having its inlet end located nearer said axis than any other portion.

19. In an engine of the character described, the combination with a cylinder, of a reciprocatory piston operating therein and including a shell having an end wall, a bearing section located in the shell and having a chamber in its top closed by said end wall, a pitman having a bearing in said section, channels formed in the pitman and section and communicating with the chamber, and means for forcing fluid through the channels.

20. In an engine of the character described, the combination with a cylinder, of a reciprocatory piston operating therein and including a shell having an end wall, a bearing section located in the shell and having a chamber in its top closed by said end wall, a pitman having a bearing in said section, channels formed in the pitman and section and communicating with the chamber, and means for forcing fluid through the channels.

21. In an engine of the character described, the combination with a cylinder, of a reciprocatory piston operating therein and including a shell having an end wall, a bearing section located in the shell and having a chamber in its top closed by said end wall, a pitman having a bearing in said section, channels formed in the pitman and section and communicating with the chamber, and means for forcing fluid through the channels.

22. In an engine of the character described, the combination with a cylinder, of a reciprocatory piston operating therein and including a shell having an end wall, a bearing section located in the shell and having a chamber in its top closed by said end wall, a pitman having a bearing in said section, channels formed in the pitman and section and communicating with the chamber, and means for forcing fluid through the channels.

23. In an engine of the character described, the combination with a cylinder, of a reciprocatory piston operating therein and including a shell having an end wall, a bearing section located in the shell and having a chamber in its top closed by said end wall, a pitman having a bearing in said section, channels formed in the pitman and section and communicating with the chamber, and means for forcing fluid through the channels.

24. In an engine of the character described, the combination with a cylinder, of a reciprocatory piston operating therein and including a shell having an end wall, a bearing section located in the shell and having a chamber in its top closed by said end wall, a pitman having a bearing in said section, channels formed in the pitman and section and communicating with the chamber, and means for forcing fluid through the channels.

25. In an engine of the character described, the combination with a cylinder, of a reciprocatory piston operating therein and including a shell having an end wall, a bearing section located in the shell and having a chamber in its top closed by said end wall, a pitman having a bearing in said section, channels formed in the pitman and section and communicating with the chamber, and means for forcing fluid through the channels.
